UNITED STATES PATENT OFFICE.

CHARLES H. GOODWIN, OF WATERBURY, CONNECTICUT, ASSIGNOR TO
THE WATERBURY BUTTON COMPANY, OF CONNECTICUT.

BUTTON OR FASTENER.

SPECIFICATION forming part of Letters Patent No. 627,110, dated June 20, 1899.

Application filed February 6, 1899. Serial No. 704,707. (No model.)

To all whom it may concern:

Be it known that I, CHARLES H. GOODWIN, residing at Waterbury, in the State of Connecticut, have invented certain new and useful Improvements in Buttons or Fasteners for Wearing-Apparel and other Articles, of which the following is a description, referring to the accompanying drawings, that form part of this specification.

The invention relates particularly to the class of so-called "glove-fasteners" in which one of the two members consists of a button-like structure or socket member containing a recess which engages and detains the co-operating member, usually of stud-like form and provided with a spring-head. The spring serves to retain the stud within the recess by reason of the slight expansion of the stud after it has passed the narrowest part of the recess. As an alternative to this form the socket or recess may be made slightly resilient and the spring feature be omitted from the stud, the co-operation being substantially the same in either case. The object of the present invention is to improve and simplify the construction of the member that contains the socket or recess. It has long been customary to secure both members to the respective flaps or edges of the garment or other article by means of tubular rivets or eyelets, and in order to insure the proper riveting up of the tubular shank of the rivet a conical or conoidal anvil-plate has been introduced into the construction. In accordance with my present invention I employ but a single piece of metal in addition to the tubular rivet, yet I retain all the advantages of appearance and of mechanical construction which have heretofore been obtained by three or four parts. The invention is of so extremely simple a nature that it will be best understood by a description of the preferred form shown in the accompanying drawings, it being of course understood that my improved button, fastener, or socket may be used with any approved form of stud of a proper size adapted to fit it.

Figure 1 is a face and edge view of the blank from which my button-cap is formed. Fig. 2 shows in side view and bottom view the

blank after its projections have been turned at right angles to the original plane of the blank. Fig. 3 shows similar views of a succeeding stage in the formation. Figs. 4 and 5 are sections on the planes 4 4 and 5 5 of Fig. 3. Fig. 6 shows the tubular rivet. Fig. 7 shows a bottom view of the completed device as applied to a piece of fabric or leather, and Figs. 8 and 9 are cross-sections of the planes 8 8 and 9 9 of Fig. 7.

Throughout the figures the same letters of reference indicate the same parts, numerals being employed to indicate different shapes or stages of such parts.

The cap portion is lettered C and the tubular rivet R. The complete construction will be best understood by tracing it through the process of formation, commencing with the blank shown in Fig. 1. The blank is provided with two sets of marginal ears c and c', which form, respectively, the inner surface of the recess which receives the stud and the rivet-engaging ears. (See Figs. 8 and 9.) Subsequently after one or two operations of suitable dies the blank is converted to the form shown in Fig. 2, the upper surface of the cap being slightly arched or domed, as in the finished article, and the edge of the cap being suitably turned or rounded over, while the respective ears c c' all lie in the cylindrical surface at right angles to their original plane. By the use of suitable dies and successive operations the ears c are turned inward and back closely against the inner surface of the cap for a portion of their length, while their extremities form the cylindrical portion of the sleeve of the cap, as shown particularly in Fig. 4. The shape which must be given to these ears c in the original blank will now be clearly understood from their use and proper fitting together in the manner described. The ears c' are merely turned inward, as shown in Figs. 3 and 5, to form lugs for catching and retaining the upset end of the tubular rivet R. (See Fig. 9.)

One peculiarity of my invention now becomes apparent by comparing Figs. 5 and 6. The tubular shank or sleeve of the rivet R when introduced into the cap lies outside of the cylindrical ends of the ears c and when

pressed against the cap in the operation of riveting the curved surface c^3 insures the proper turning and upsetting of the end of the rivet and guides the upset flange during the riveting operation toward and beneath the lugs formed by the ears c' , all as indicated by arrows in Fig. 5 and by the finished structure in Fig. 9. Consequently my improved structure is characterized by the formation from a single blank of the cap, the riveting-anvil, and the riveting projections or lugs c' . The finished article indicates this construction only by the appearance of the ends c within the recess of the cap or button, as shown in Figs. 7, 8, and 9.

The advantages of my invention will be apparent to those skilled in the art.

What I claim as the novel and characteristic features of my invention are the following:

1. A button or fastener consisting of a cap provided with inwardly-turned marginal portions and a rivet the tubular shank or sleeve

of which is upset against and turned outward by said inwardly-turned portions and engaged by and beneath separated marginal ears of the said cap, substantially as set forth. 25

2. A button or fastener cap consisting of a piece provided with two sets of integral marginal ears one set constituting rivet-engaging 30 lugs and the other set being distinct therefrom and constituting rivet-upsetting devices or anvils, substantially as set forth.

3. A button or fastener cap having two sets of bent marginal ears, one set being turned 35 inward to form rivet-holding lugs and the other set being turned inward in the intervals between such lugs and constituting anvils for upsetting the rivet, substantially as set forth.

Signed this 27th day of January, 1899, at 40 Waterbury, Connecticut.

CHARLES H. GOODWIN.
